UNITED STATES PATENT OFFICE.

JOSEPH R. TORREY, OF WORCESTER, MASSACHUSETTS.

CUSHIONED RAZOR-STROP.

SPECIFICATION forming part of Letters Patent No. 240,342, dated April 19, 1881.

Application filed September 18, 1880. (Model.)

To all whom it may concern:

Be it known that I, JOSEPH R. TORREY, of the city and county of Worcester, and Commonwealth of Massachusetts, have invented certain new and useful Improvements in Cushioned Razor-Strops; and I do hereby declare that the following is a full, clear, and exact description of the same, reference being had to the accompanying drawings, forming a part 10 of this specification, and in which—

Figure 1 represents a top view. Fig. 2 represents an edge or side view of the strop shown in Fig. 1, and Fig. 3 represents a cross-section on line $x\ x$, Fig. 2. Figs. 4, 5, and 6 represent 15 views of a modification, as will be hereinafter more fully described.

To enable those skilled in the art to which my invention belongs to make and use the same, I will proceed to describe it more in detail.

The nature of my invention consists of a cushioned elastic strop, and also in the combination of said elastic cushioned strop with a central wooden supporting part, as will be 25 hereinafter more fully described.

In the drawings, the parts marked A represent the cushioned elastic stropping parts. As shown in Figs. 1, 2, and 3, the cushioned elastic stropping parts A are stretched and 30 combined with central wooden supporting parts B, which are extended to form the handle C. The ends D D of the cushioned stropping part A are stretched down on the top and bottom sides of the central wooden supporting 35 part B from the point B' to the point E, where they are properly secured to the base of the part B, as indicated at E', Figs. 1 and 2 of the drawings, and said cushioned elastic stropping parts A are so stretched as to leave 40 spaces aa nearly, if not quite, through between the central wooden supporting part B and the inside of the cushioned parts A.

The cushioned parts A, as shown in Figs. 1, 2, and 3, are formed as follows: A paper sheath, 45 b, of sufficient length to make one side of the strop, is provided with a wide layer of leather, c, and upon the inside of that with another layer of leather, about two-thirds as wide, and between such layers and the paper sheath b 50 are evenly-arranged layers of cotton or wool, e, in sufficient numbers to keep the parts A well extended. The outer coating f of the strop is

formed or made from leather. The layers of leather c d are arranged upon the inner sides of the stropping parts A, as indicated in Fig. 3, by which arrangement proper supports are given to the stropping parts A should they be forced down when in use, so as to strike against the central wooden supporting part B.

The outer ends of the stropping parts A, 60 Figs. 1, 2, and 3, are fastened to the front end of central wooden supporting part B, at the point B', by lapping the ends of the leather casings or coatings f, and then nailing said lapped ends to the front end of the wooden supporting part B. Said lapped ends of leather coatings f may be first glued together to make a more finished job. The stropping parts A are nailed to the wooden supporting part B at the point E, after which the nail-heads may 65 be covered by a leather trimming glued on, and which trimming is indicated by full lines in the drawings.

In Figs. 4 and 5 are represented top and edge views of the cushioned elastic parts A 75 when used without any central wooden supporting part; and, instead of layers of leather c and d, the leather part f is lapped at one side, as shown at g g, and a leather holding end, F, is fastened to its outer end and provided with 80 a hole, h, for hooking or hanging it upon a hook or hanging-pin, while it is held taut for use by the leather handle G, fastened to its other end. It is stuffed or filled with layers of cotton or wool e, the same as in Figs. 1 and 85 2; and Fig. 6 represents a section upon line $x'\ x'$, Fig. 5 of the drawings.

It will be observed that each stropping part is free to move laterally, excepting at its extreme ends—that is, it is not confined, excepting 90 at its extreme ends—and as a result thereof it can vibrate or yield slightly in a lateral direction while in use, thereby producing a more perfect action upon the razor-edge than if such stropping part was confined at its edges 95 from end to end, as in the old devices prior to my invention.

It is important, in making my cushioned elastic stropping parts A, that the different layers of cotton or wool should all be arranged 100 uniformly and evenly when finally left for use in the sheath b or leather sheath f; and to accomplish this I first take a thin piece of card-board of the proper width and then carefully arrange

the layers of cotton or wool upon this piece of card-board until a sufficient pile of fibrous material has been obtained to fill the sheaths *b* or *f*, as the case may be, when another piece of 5 card-board is placed on top of the fibrous material, and the whole then carefully run into the sheath, after which the pieces of card-board are carefully drawn out, one after another, the fibrous material being held from being displaced or drawn out with the pieces of card-board.

The stropping parts *A*, it will be observed, are kept extended longitudinally in a suitably taut manner while in use by the central wooden 15 supporting part *B*, Figs. 1, 2, and 3, and by the handle *G*, Figs. 4 and 5.

By the combination of the elastic stropping part *A* with the central part, *B*, so that the same is held firm and secure at each end of 20 the central part, *B*, while, at the same time, the said elastic cushioned stropping part is supported and kept from too great deflection while in use by coming in contact with the central part, a far better and more desirable 25 result is obtained in the operation of sharpening the razor than would be the case if the said stropping elastic surfaces were allowed to bend down when the razor was drawn over them, as would be the case if the fastened ends 30 were extended by means of straining mechanism. Therefore it will be seen by those skilled in the art to which my invention belongs that I have devised a strop in which the elasticity is preserved, and the surface 35 over which the edge of the razor is drawn is made to assume the desired shape for imparting a perfect edge, since when the central por-

tion of the elastic part *A* is depressed the inner surface is pressed against and supported by the rigid central part, *B*, thereby causing 40 the edges of the outer surface to be "fullled" or pushed out, to act upon the edge of the razor and give it a fine cutting-edge.

Having described my improvements in cushioned razor-strops, what I claim therein as 45 new and of my invention, and desire to secure by Letters Patent, is—

1. In a razor-strop, the combination of a cushioned leather elastic stropping part *A*, fastened rigidly and securely at the ends of the central 50 part *B* only, and left free to work without longitudinal tension along the entire lengths of the sides of the said central part, *B*, while at the same time being supported on the inner sides thereof when in use, all as and for the 55 purposes set forth.

2. The mode or process hereinbefore described of making elastic cushioned stropping parts *A* of a razor-strop, consisting, first, of the evenly piling of layers of cotton or wool *e* 60 upon a thin piece of card-board until a sufficient thickness to form the desired cushion is obtained, then applying another piece of card-board, and then inserting combined layers of fibrous material and card-board in the stropping-sheath upon the layers of leather *c d*, and finally withdrawing the card-board pieces, one 65 at a time, so as to leave the fibrous layers extended evenly from end to end in the sheath, all as shown and described.

JOSEPH R. TORREY.
